(57) **CLAIM**

The ornamental design for a touch sensor type keyboard for computer, as shown and described.

DESCRIPTION

FIG. 1 is a top plan view of a touch sensor type keyboard for computer;

FIG. 2 is a front view thereof;

FIG. 3 is a right-side view thereof;

FIG. 4 is a left-side view thereof;

FIG. 5 is a rear view thereof;

FIG. 6 is a bottom view thereof;

FIG. 7 is a front view thereof with the feet extended;

FIG. 8 is a left-side view thereof with the feet extended;

FIG. 9 is an enlarged partial view thereof designated by the dot-dash, chain-like broken line area 9 in FIG. 1;

FIG. 10 is an enlarged partial view thereof designated by the dot-dash, chain-like broken line area 10 in FIG. 1; and,

FIG. 11 is a top plan view thereof in a state in which the power is turned off.

The broken lines shown in FIG. 1 that are immediately surrounding all of the indicia and adjacent to the shade lines, represent the bounds of the central portion of the claimed design, while all other lines are directed to environment and form no part of the claimed design.
